UNITED STATES PATENT OFFICE.

ALPHONSO TAURMAN, OF RICHMOND, VIRGINIA.

SWITCH-TONGUE-CONTROL DEVICE.

1,288,744.

Specification of Letters Patent. Patented Dec. 24, 1918.

Application filed April 15, 1918. Serial No. 228,647.

To all whom it may concern:

Be it known that I, ALPHONSO TAURMAN, a citizen of the United States, residing at Richmond, in the county of Henrico, State 5 of Virginia, have invented certain new and useful Improvements in Switch-Tongue-Control Devices; and I do hereby declare the following to be a full, clear, and exact description of the invention, such as will enable others skilled in the art to which it 10 pertains to make and use the same.

My invention is directed to new and useful improvements in devices for yieldably holding the movable tongue of a switch frog 15 against switching movement, and more particularly of that type including a spring urged cam member controlling a tongue connected crank and engaging a suitable stationary member whereby to continuously 20 urge the tongue to desired position.

It is the object of the present invention to simplify and strengthen the structure, and to increase the efficiency of devices of this character more particularly by the provision 25 of an arrangement of parts of such rugged construction as to obviate the necessity for a fluid tight housing for protecting the cam mechanism from the elements and from contact with the usual mud and other foreign 30 matter which would be encountered by a device inset along the track.

A further and more specific object resides 35 in the provision of a switch tongue controlling device of this nature which may be readily adapted to urge the switch tongue to switching position at either side of the switching frog, dependent upon the disposition 40 of the tongue to either side of an intermediate position, or which may be actuated to urge the tongue toward only one side of the frog from whichever position the tongue may assume, thus forming in the first instance what is commonly known as a switch lock, and in the other instance forming what 45 is known as a spring switch.

A still further object resides in the provision of a switch tongue controlling mechanism of this nature which is most readily accessible to provide adjustment of the 50 spring thereof, to compensate for wear or for the weakening of said spring.

With the above and other objects and advantages in view, the invention resides more particularly in the novel combination, for-

mation and arrangement of parts herein- 55 after described and particularly pointed out in the appended claims.

In the accompanying drawings:

Figure 1 is a plan view of a switch frog showing my improved tongue controlling 60 device associated therewith, the cover of the casing of the device being removed.

Fig. 2 is an enlarged vertical sectional view through the device on a plane indicated by the line 2—2 of Fig. 1, and showing the 65 device arranged as a switch lock and holding the switch tongue in one limit of movement.

Fig. 3 is a vertical sectional view through the casing transversely of the plane of the first section and showing the main shaft and 70 cams in elevation.

Fig. 4 is a similar view, showing the relation of parts assumed in one of the spring urged switching positions of the tongue.

Fig. 5 is a similar view, but showing the 75 device adapted for use in forming a "spring switch".

Fig. 6 is a transverse sectional view on the line 6—6 of Fig. 2.

Referring now more particularly to the 80 drawings, 10 designates a switch frog of entirely conventional nature, having a single track section 11 at one end, a pair of track sections 12 at its other end and having a switch tongue 13 pivotally mounted therein 85 and adapted to be thrown by any suitable means (not shown).

My improved tongue controlling device comprises a casing formed of a bottom 14, walls 15 and a removable cover 16, the details of the cover and its mounting on the casing being of any suitable nature to provide for a ready removal of the cover and a fair degree of protection for the interior of the casing. An attaching lug 17 is projected 95 from one side wall of the casing, and this lug and said wall are apertured for the reception of bolts 18 securing the casing against one side of the frog adjacent the free end portion of the tongue, the top of the 100 casing being substantially flush with the top of the frog.

For mounting the control mechanism in the casing, a vertical shaft 19 is secured in one end portion of the casing by threaded 105 engagement of its lower end in an aperture 20 in the bottom of the casing, the extremity of the shaft projecting below said bottom

and having threaded thereon a nut 21 bearing against the casing and held by a locking pin 22 passed therethrough and through the shaft. The upper end of the shaft is 5 unsecured and projects into a recess 23 in the bottom of the cover. Engaged on the shaft and seated on the bottom of the casing is a stationary cam disk 24 having diametrically opposed angular cam projections 10 25 thereon having cam faces disposed at an angle of substantially 120 degrees to each other and meeting at a line extending perpendicular to and intersecting the axis of the shaft. Slidably and rotatably mounted 15 on the shaft is a second cam disk 26 having diametrically opposed cam projections 27 thereon corresponding in size and shape to the projections 25 whereby opposite faces of the cam projections 25 and 27 may be 20 engaged to urge the cam disk 26 rotatably in either direction under the influence of an expansile coil spring 28 mounted on the shaft and bearing against the disk 26 and against a cupped bearing plate 29 adjust- 25 ably held on the upper end of the shaft by a nut 30. Extending from the cam disk 26 longitudinally of the casing is a crank arm 31 which carries at its free end a wrist pin 32 on which is pivotally mounted 30 an eye 33 at one end of a rod 34 which extends outwardly of the casing through an aperture 35 in the outer side wall thereof. The outer end of the rod 34 is threaded into one end of a sleeve 36 which has one end 35 bifurcated to receive between its furcations in pivotal connection the eye 37 of an eye bolt 38 which is passed through a lug 39 depending from the switch tongue 13 and which is rigidly secured in said lug by a nut 40 40 threaded on its outer end and binding the lug between said nut and an annular rib 41 on its inner portion. A lock nut 42 is threaded on the rod 33 and bears against the end of the sleeve 36 to prevent the parts 45 from possibly working loose.

By this connection between the crank arm 31 and the switch tongue, compensation is had for the vertical movement of the cam disk 26 incidental to the rotative engagement of its cam face with the cam face of the fixed disk 24, it being noted that the eye 33 of the connecting rod 34 is sufficiently loose to permit a rocking movement of the rod on the wrist pin 32. It is further noted 50 that the axis of the bolt 38 is located in a plane mid-way of the parallel planes including the axis of the wrist pin 32 in its extreme operative positions procuring a horizontal rocking movement of the connecting 55 rod 34, and thus the rod is subjected to a minimum rocking motion which is readily taken up by looseness of the pivot bolt of the sleeve 36. An adjustment of the connection between the tongue 13 and crank 60

arm 31 may obviously be effected by threading movement of the rod 34 in the sleeve 36 to thus coördinate the oscillating movements of said tongue and crank, it being noted that the engagement of the tongue with the sides of the switch frog limits the 65 70 pivotal movement of the crank arm.

In the use of the controlling device as a spring switch whereby the switch tongue is resiliently urged to the limit of each switching position upon movement past an 75 intermediate point, the arrangement shown specifically in Figs. 2, 3, and 4 is employed wherein the apex line of the cam projections 25 extends substantially parallel to the longitudinal axis of the switch frog whereby 80 in the central position of the switch tongue, as shown in Fig. 3, the apex lines of the cam projections of the fixed and rotative cam disks 24 and 26 respectively coincide. Thus upon movement of the switch tongue to 85 either side of its central position, it will be resiliently urged to the corresponding limit of switching movement, and will be prevented from remaining in said central 90 position inasmuch as under influence of the 95 spring 28 the cam disk 26 would rotate to either side of the apex line of the cams 25. A positive means is thus afforded for preventing the occurrence of what is commonly known as a split switch wherein the tongue remains in intermediate position or moves from one position to another while cars are passing thereover.

It is noted that in the operation just described approximately one-half of each of the operative faces of the cam projections is utilized, and this extent of the cam face is provided for purpose of transforming the switch controlling device when desired into what is commonly known as a spring switch, 100 wherein the switch tongue is resiliently urged to one side of the switch frog from whichever position it may assume. In this use of the device, the stationary cam disk 24 is shifted rotatively about the bolt 18 until 105 its apex line extends obliquely of the switch frog, as shown in Fig. 5. One side face of each cam projection 27 of the rotating disk 26 thus has movement over practically the entire extent of a side face of the corresponding fixed cam projection 25 and never passes the apex line of the cam projection, the range of cam movement thus afforded providing for complete switching movement 110 of the switch tongue and serving to always 115 urge the switch tongue in one direction. While the means for securing the stationary cam disk 24 to the bottom of the casing comprises in the present instance rivets 43, passed through said bottom and casing, it 120 is obvious that a more readily detachable means for securing the cam disk may be employed, although necessity for adjustment 125

for the cam disk would usually occur only incidental to the installation of the controlling device.

An exceedingly simple device has thus 5 been provided which is strong and durable in nature and which will operate efficiently under all conditions of use, it being noted particularly that the rugged and simple structure employed renders the device independent of the necessity for providing a 10 fluid tight housing for any parts thereof.

The provision of a crank arm formed directly on the switch moving cam disk 26, and the pivotal securement of the connecting rod 34 of this crank arm with the switch tongue conduce particularly to the simplicity and rugged nature of the structure in the avoidance of any relatively movable portions in the structure between which 20 mud or silt might pack to clog the operation.

What is claimed is:

1. A switch controlling device comprising a casing, a cam member movable in the casing, a stationary member engageable by 25 said movable cam member, means urging the cam member toward the stationary member to procure rotation of the cam member in such movement, a crank arm on the cam member and a switch tongue connection 30 for the crank arm.

2. A switch controlling device including a casing, a cam member rotatably and slidably mounted in the casing, a stationary member engageable by said cam member, a 35 spring resiliently urging said cam member to engagement with said stationary member, an operating rod connected at one end with the cam member and extending outwardly of the casing and means for pivotally connecting the other end of said rod with a switch tongue.

3. A switch controlling device including a casing, a cam member rotatably and slidably mounted in said casing, and including 45 oppositely inclined cam faces, means for connecting said cam member with a switch tongue, a spring resiliently urging said cam member in one direction and a normally stationary member engageable by the cam member 50 to procure movement thereof under influence of the spring, said stationary member being shiftable to engage one face of the cam member or to engage both faces thereof whereby to vary the control of the switch 55 tongue.

4. A switch controlling device comprising a casing, a shaft therein, a cam disk normally fixed on the shaft, a cam disk slidably rotatable on the shaft, co-operating projections on said cam disks, a crank arm on 60 the rotatable cam disk, means for connecting said crank arm with a switch tongue, a coil spring on the shaft bearing against the

second named disk and an adjustable tensioning member on the shaft engaging said 65 coil spring.

5. A switch controlling device comprising a casing, a shaft therein, a cam disk slidably rotatable on the shaft and having a cam projection thereon, a stationary cam 70 projection engageable by the first projection, a spring engageable with said cam disk, a crank arm on the disk and a switch tongue connection for said crank arm.

6. A switch controlling device including 75 a casing, a cam member movable in the casing, a stationary member engageable by said movable cam member, means urging the cam toward the stationary member; a crank arm on the movable cam member, a member 80 adapted for securement to a switch tongue, a sleeve having one end pivotally connected with the said attaching member and a rod having one end secured to the crank arm and its other end threadedly engaged in the 85 other end of the sleeve.

7. A switch tongue controlling device including a casing, a pair of relatively movable members therein having cam engagement, means resiliently urging said members 90 together, a crank arm formed on one of said members and a rod pivotally connected with said crank arm and adapted for pivotal connection with a switch tongue.

8. A switch tongue controlling device including a casing, a pair of relatively movable members therein having cam engagement, means resiliently urging said members together, means for connecting one of said members with a switch tongue, a pair 100 of outstanding intersecting cam faces on the specified member engageable with the other member and means for holding the other member against cam movement in a manner permitting shifting of said other member to 105 engage for cam action either or both of the cam faces of the first specified member.

9. A switch tongue controlling device including a casing, a shaft secured to and extending inwardly from one wall of the 110 casing, a stationary cam member adjacent the juncture of the wall and casing, a cam disk rotatably and slidably mounted on the shaft and including a portion engageable with the stationary cam member, a crank 115 arm on the cam disk, a rod pivotally connected with the crank arm and adapted for pivotal connection with a switch tongue and a spring on the shaft urging the cam disk toward the stationary cam member.

In testimony whereof I affix my signature in the presence of two witnesses.

ALPHONSO TAURMAN.
